TIME SWITCH

Carl E. Sundberg, Quincy, Mass., assignor to
 Albert & J. M. Anderson Manufacturing Company, Boston, Mass., a corporation of Massachusetts

Application December 1, 1932, Serial No. 645,228

3 Claims. (Cl. 200—37)

This invention relates to a time switch.

One object of the invention is to provide a novel and improved time switch which is simple in construction, positive and efficient in operation, and lends itself to economical manufacture.

A further object of the invention is to provide a novel, automatic time switch embodying a synchronous motor, and whose construction is such as to lend itself to economical manufacture and positive and efficient operation.

With these general objects in view and such others as may hereinafter appear, the invention consists in the time switches, and in the various structures, arrangements and combinations of parts hereinafter described and particularly defined in the claims at the end of this specification.

In the drawings illustrating the preferred embodiment of the invention, Fig. 1 is a front elevation of the improved time switch; Fig. 2 is a side elevation of the time switch shown in Fig. 1; Fig. 3 is a detail of the switch actuating mechanism to be referred to; and Fig. 4 is a rear elevation of the time switch shown in Fig. 1 with portions of the cover plate broken away.

In general, the invention contemplates a time switch, and preferably an automatic time switch, which may be used for controlling an electrical circuit, or for controlling any other switch member, and as herein shown the invention is embodied in a synchronous motor operated time switch for controlling an electrical circuit which is designed to close the circuit, and open the circuit, once during each twenty-four hours.

Referring now to the drawings, the illustrated time switch is provided with a synchronous motor 10 mounted in a supporting frame 11 and supplied with current through the leads 12. The synchronous motor may be of any usual or preferred construction designed to be operated in accordance with a master clock to enable the motor shaft to be utilized as a time element. Provision is made for operatively connecting the motor shaft 13 with a time dial 17, and the latter may and preferably will be graduated into twenty-four hours and parts thereof, and will be hereinafter referred to as the 24-hour dial. As herein shown, the motor shaft is provided with a pinion 14 meshing with a ring gear 16 mounted upon a worm shaft 18. The worm shaft 18 is provided with a worm 20 which meshes with a worm wheel 22 mounted upon a second worm shaft 24 journaled in two screw bearings 26 in brackets 28, as shown. The shaft 24 is also provided with a worm 30 which meshes with a worm

wheel 32 on a shaft 34. The shaft 34 is provided with a pinion 36 which is connected to the gear train 38, 40, 42, to a hub 44 mounted upon the shaft 46 and to which hub the 24-hour dial 17 is secured to rotate therewith. The ratio of the 5 gearing referred to is such that the shaft 34 makes a complete revolution once an hour, and may therefore be regarded as the minute shaft, and a minute dial 37 is herein shown secured to the end of the shaft 34, and an operating knob 10 39 is provided for a purpose to be described.

Provision is made for enabling the shaft 34 to be rotated independently of the synchronous motor 10, and the gearing connections between the synchronous motor 10, and the gearing connections between the synchronous motor and the shaft 34, when it is desired to set the dials 17 and 37 to correct inaccuracies in their position, in the event that the operation of the synchronous motor has been interrupted for any reason, 20 and for this purpose a friction connection is provided between the shaft 34 and the worm wheel 32, and as herein shown the worm wheel 32 is free on the shaft 34 and frictionally held against a collar 39 pinned to the shaft 34, by a coil spring 25 41, the second end of which abuts against a second collar 43 also pinned to the shaft. In this manner, during normal operation the rotations of the synchronous motor are transmitted from the worm wheel 32 to the shaft 34. When 30 it is desired to modify the position of the dials 17, 37, the operator may turn the shaft 34 by means of the operating knob 39 without effecting the rotation of the worm wheel 32 and the synchronous motor geared thereto.

In the illustrated time switch, a pair of electrical circuits are arranged to be controlled by pivoted mercury tube switches 61, 63 of any usual or preferred construction and which are herein shown as secured in clips 65 attached to a bracket 40 67 pivoted upon studs 70, 72 in the frame of the time switch. In the operation of the time switch, when the mercury tubes 61, 63 are tipped into the position shown in Fig. 3, the circuits are closed by the bodies of mercury within the respective tubes, and when the tubes are tipped into the position shown in Fig. 4, these circuits are opened. Provision is made for effecting the tipping of the tubes at the particular time during each twenty-four hours in the operation of 50 the time switch, corresponding to the position occupied by pallets or pointers 71, 73, respectively. The pointers are provided with the usual projections on their under sides which fit into slots 74 in the 24-hour dial 17 to adjustably con- 55

nect the pointers with the dial. The pointer 71 may be regarded as the "on" pointer and the pointer 73 as the "off" pointer, so that when the time during the 24-hour period arrives corresponding to the position at which the "on" pointer 71 is set, provision is made for effecting tipping of the mercury tubes 61, 63 to close the circuits, and when the time arrives corresponding to the position of the "off" pointer 73, provision is made for effecting the tipping of the tubes 61, 63 to open the circuits.

As herein shown, the hub 44 to which the spur gear 42 is secured is connected to the 24-hour dial 17 by a hub 45 on the dial which fits over 15 and is keyed to the end of the hub 44. The hub 44 is made hollow and has both the sleeve 80 and the shaft 46 extended therethrough. At one end the sleeve 80 is secured to the "off" pointer 73 and the shaft 46 is secured at the corresponding 20 end to the "on" pointer 71. At the other end of both the sleeve and shaft, the sleeve 80 is connected to a cam disk 50 and the shaft 46 is connected to a second cam disk 52. The cam disk 52 has cooperating with it a cam finger 54, and the cam disk 50 has cooperating with it a cam finger 56. The fingers 54 and 56 are formed on levers pivoted at 60 and having extensions or arms 64, 62, respectively whose ends are located on opposite sides of a plane through the pivot 60 and, 30 which are normally urged together by a coil or helical spring 66 having its free ends engaging the extensions or arms 62, 64, as shown in Fig. 3. As a result of this construction, the spring 66 tends to hold the fingers 54, 56 in contact with the cam 35 disks 50, 52 and urges them to drop into notches or recesses 65, 67 in the disks when such recesses are brought into register with the fingers during the rotation of the cam disks with the 24-hour dial 17 and the hub 44 which is driven through the 40 gearing above described from the synchronous motor. The movement of the extended ends 64, 62 of the fingers 54, 56, when the fingers drop into the recesses 65, 67 in the cam disks, is utilized to effect the movement of the switch member or 45 members herein shown as the mercury tubes 61, 63, and as herein shown this is accomplished by providing one of the pivots 70 upon which the bracket 68 is pivoted with a crank or arm 90 having a stud 92 designed to be engaged by the extensions 62, 64. The stud 92 is connected by a 50 spring 94 to a fixed part of the frame of the switch, which operates to hold the tubes in either circuit closing or open circuit position until the next operation of the switch and while either arm 55 62, 64 is being moved away from the stud 92 by the cam-shaped recesses 67, 65 in the disks 50, 52. Stops 93 are provided upon the frame for limiting the movement of the lever 90 in opposite directions.

60 In the operation of the switch, assuming the parts to be in open circuit position, such as is shown in Fig. 4, when the cam disk 52 which may be regarded as the "on" cam disk has rotated sufficiently to bring its recess into register with the 65 finger 54, the latter will fall into the recess under the influence of the spring 66 and this movement will cause the extension 64 of the finger 54 to move the stud 92 and the mercury tubes into circuit closing position, such as is shown in Fig. 3.

70 The switch parts are held in this position by the spring 94 while as the cam disk 52 continues rotation, the finger 54 rides up on the inclined surface 88 of the recess, thereby operating to move the extension 64 to the right, viewing Fig. 3, and 75 away from the stud 92 placing the parts in con-

dition for the next succeeding operation. Thereafter, when the recess 67 in the second or "off" cam disk 50 comes into register with its finger 56, the latter moves into the recess, operating to cause the extension 62 to move the stud 92 to the right, viewing Fig. 3, thereby effecting the tipping of the mercury tubes into the open circuit position shown in Fig. 4. During the operation of the switch, the spring 94 also assists in effecting a rapid movement of the parts into either open circuit or closed circuit position after the stud 92 has passed the center line in its movement under the influence of either of the extensions 62, 64.

While as illustrated herein the different features of the invention are shown as embodied in 15 a time switch having a synchronous motor as the time element, it will be understood that they may be embodied with advantage in other forms of time switches, and also while as herein shown two mercury switches 61, 63, are employed for controlling two circuits, it is to be understood that more switches may be embodied in the time switch if formed advantageous.

From the description thus far, it will be observed that the present construction of time 25 switch is simple, may be economically manufactured, and is positive and rapid in operation.

While the preferred embodiment of the invention has been herein illustrated and described, it will be understood that the invention may be 30 embodied in other forms within the scope of the following claims.

Having thus described the invention, what is claimed is:—

1. In a time switch, in combination, a rotatable shaft, a plurality of sleeves concentrically mounted on said shaft, a time dial fast on one of said sleeves to rotate therewith, pointers fast on said shaft and another of said sleeves and cooperating with said time dial to effect rotation 40 by said time dial of said shaft and pointer carrying sleeve, a cam disk fast on said pointer-carrying sleeve and provided on its circumference with a cam-shaped recess, a second cam disk fast on said shaft and provided on its circumference with 45 a cam-shaped recess, a switch member, pivoted levers cooperating with said cam disks and having fingers to engage the circumference of said disk and hold the switch member from movement and to enter said cam recesses and permit said 50 switch member to be moved, and a spring co-operating with said levers to maintain their fingers in operative relation with said cam disks to enter the said recesses and effect movement of said switch member. 55

2. In a time switch, in combination, a rotatable shaft, a plurality of sleeves concentrically mounted on said shaft, a gear fast on the outer sleeve, a disk fast on the inner sleeve and provided on its circumference with a cam-shaped 60 recess, a disk fast on said shaft and provided on its circumference with a cam-shaped recess, a time dial fast on said outer sleeve, pointers fast on said inner sleeve and said shaft and co-operating with the said time dial to enable the latter to 65 rotate said inner sleeve and shaft, pivoted levers having fingers extended from one side of said pivot and co-operating with said cam disks and having arms extended from the other side of said pivot, a switch member having a device interposed between said arms, a spring having its free ends engaged with said arms to effect movement of said device and switch member, and a second spring to hold said switch member while an arm 70 75

of said levers is being moved by its cam disk away from the device on said switch member.

3. In a time switch, a rotatable shaft, a plurality of sleeves concentrically mounted on said shaft, a gear permanently secured on the outer sleeve, cam disks permanently secured on the inner sleeve and shaft, and provided on their circumferences with cam-shaped recesses, pointers permanently secured to said inner sleeve and shaft, a time dial permanently secured to said outer sleeve and having slots in the periphery thereof to engage with said pointers to enable

said time dial to rotate said inner sleeve and shaft, and to permit said pointers to be independently and selectively indexed upon said time **dial**, concentrically pivoted levers having fingers extending from one side of the pivot cooperating with said cam disks, and arms extending from the other side of the pivot, a switch member, a device thereof interposed between said arms and cooperating therewith, whereby the actuation of said lever fingers by said cams actuate said switch member by said lever arms. 5

CARL E. SUNDBERG.
